CONTAINER STOPPER OR THE LIKE

Louis Brodsky, Parlin, N.J., assignor to E. R. Squibb & Sons, Inc., New York, N.Y.

Filed May 19, 1971, Ser. No. 145,102

Term of patent 14 years

Int. Cl. D9—07

U.S. Cl. D9—264

FIG. 1

FIG. 3

FIG. 1 is an isometric view of a container stopper or the like showing my new design, the side not shown being a mirror image of the side shown;

FIG. 2 is a top plan view; and

FIG. 3 is a bottom view.

I claim:

The ornamental design for a container stopper or the like, as shown and described.
